UNITED STATES PATENT OFFICE.

JOHN POTURNAJ, OF SILVER SPRINGS, NEW YORK, ASSIGNOR OF ONE-HALF TO
FRANCIS J. HANLEY, OF SILVER SPRINGS, NEW YORK.

COMBINATION PADLOCK.

Application filed July 18, 1928. Serial No. 293,922.

This invention relates to certain new and useful improvements in combination padlocks and has for its primary object to provide a padlock comprising a casing with the 5 legs of the shackle passing therethrough and with a plurality of disk tumblers controlling operation of a sliding locking pin for the shackle legs with a plurality of handles for operating the interengaged tumblers and 10 with a lever for shifting the locking pin against spring tension thereon into locking engagement with the shackle leg to permit movement of the disk tumblers for holding the locking pin engaged with the shackle 15 leg.

With the above and other objects in view that will become apparent as the nature of the invention is better understood, the same consists in the novel form, combination and 20 arrangement of parts hereinafter more fully described, shown in the accompanying drawings and claimed.

In the accompanying drawings:—

Figure 1 is a side elevational view of a 25 combination padlock constructed in accordance with the present invention;

Figure 2 is an edge elevational view of the same showing operating handles for the disk tumblers extending through slotted openings in the side wall of the casing;

Figure 3 shows perspective views of the disk tumblers and sliding tumbler plate carrying the shackle leg locking pin;

Figure 4 is a top plan view of the lock 35 with the cover removed showing the shackle in its locked position;

Figure 5 is a cross-sectional view taken on line 5—5 of Figure 4;

Figure 6 is a top plan view of the lock 40 with the cover removed and showing the shackle leg in its released position; and

Figure 7 is a cross-sectional view taken on line 7—7 of Figure 6.

The lock casing disclosed being of circular 45 form comprises a bottom wall 1, an annular side wall 2 and a cover wall 3 secured to the annular side wall 2 by the rivet bolt 4, the annular side wall 2 of the lock casing being provided with openings for the passage of the relatively short and long legs 50 6 and 7 respectively of the shackle 8. The annular side wall 2 of the lock casing is provided with three slotted openings 9, 10 and 11 for the passage of tumbler operating handles to be presently described, while

the opposite side of the wall 2 upon its inner face carries a block 12 grooved for the passage of the shackle leg 7 that has a notch 13 therein to be aligned with the vertical slot 14 in the block 12 to receive the locking pin of the lock mechanism for retaining the shackle locked in the casing.

The detailed construction of the lock mechanism comprising a plurality of disk tumblers and operating handles together with a 60 sliding tumbler plate and a locking pin for the shackle which is shown more clearly in Figure 3, the tumbler plate 15 having a slotted opening 16 therein received on the bolt 4 and is slidably mounted upon the bottom wall 1 of the lock casing as shown in Figures 5 and 7, the tumbler plate 15 being further guided in its sliding movement by the pin 17 positioned between the forked end 18 of the tumbler plate. A perpendicular 70 locking pin 19 is carried by the sliding tumbler plate 15 and is adapted to be moved into the registering notch and slot 13 and 75 14 formed respectively in the shackle leg 7 and locking block 12. The sliding tumbler 80 plate 15 is normally influenced in a direction away from the block 12 by the leaf spring 20 anchored at one end as at 21 to the inner face of the annular side wall of the lock casing with the free end thereof selectively positioned in the desired notch 22 formed in the adjacent edge of the tumbler plate 15, the spring end being retained in position in the notch by the upper guide finger 23 carried by the bottom wall of the lock casing.

The series of disk tumblers comprises a tumbler disk 24 having a central opening 25 received on the casing bolt 4 and a peripheral notch 26 of a size to receive the locking pin 19, the tumbler disk 24 carrying a radial 95 handle 27 extending through the slotted opening 9 in the side wall of the lock casing with the outer end thereof bent as at 28. The inner end of the handle 27 adjacent the tumbler disk 24 is provided with a shoulder 29 forming a tumbler lug engageable with a tumbler lug upon another disk tumbler. The tumbler disk 30 having the central opening 31 is then placed on the bolt 4 and has a peripheral notch 32 to receive the locking pin 19 and 100 also a pair of spaced depending tumbler lugs 33 and 34. The tumbler disk 35 having the central opening 36 and peripheral notch 37 is mounted upon the bolt 4 engaged with the tumbler disk 30 and also has a tumbler lug 110

engaging shoulder 38 at its point of connection with the operating handle 39 that extends through the slotted opening 10 in the side wall of the casing. The tumbler disk 40 is 5 mounted upon the tumbler disk 35 and has a central opening 41 to accommodate its mounting and also a peripheral notch 42. An upstanding tumbler lug 43 is carried by the peripheral edge of the tumbler disk 40 10 which also carries a depending tumbler lug 44. The tumbler disk 45 having the central opening 46 and peripheral notch 47 is mounted upon the bolt 4 contacting the tumbler disk 40 and carries a handle 48 extending 15 through the slotted opening 11 of the casing with the outer end thereof bent as at 49. A top tumbler disk 50 having the central opening 51 is mounted upon the upper end of the bolt 4 and has a peripheral notch 52 and a depending tumbler lug 53. A washer 54 is mounted upon the upper end of the bolt beneath the cover 3 and retains the several tumbler disks engaged with each other.

When the several tumbler disks have been 25 positioned to dispose all of the peripheral notches therein in alignment with the locking pin 19, the spring 20 moves the locking pin and sliding tumbler plate 15 to position the pin in said notches as shown in Figure 6 30 and when it is desired to move the locking pin into the notch 13 and slot 14 in the shackle leg 7 and block 12 respectively, the lever 54 which is pivoted as at 55 in the casing 35 with the operating end 56 thereof extending through a wall slot is operated to cause the end 57 thereof to engage the inner end of the tumbler plate 15 to move the same against the tension of the spring 20.

When it is desired to release the shackle 40 from the locked position shown in Figure 4 and in which position the several disk tumblers are disposed so that the peripheral notches thereof are displaced from alignment with the locking pin 19, the several 45 handles 27, 39 and 48 are moved to the lower ends of the slots 9, 10 and 11 as shown in Figure 4. The handle 48 is first moved through the full length of the slot to the upper end thereof without operating any of 50 the other tumbler disks. During such movement, the notch 47 in the tumbler disk 45 carrying the handle 48 is moved slightly beyond the locking pin 19. The handle 39 is then moved to the upper end of the slot 10 55 and the shoulder lug 38 carried by the tumbler disk 35 engages the depending lug 44 upon the tumbler disk 40 to move said disk, while the upstanding tumbler lug 43 on the tumbler disk 40 positions the edge notches 42 and 52 60 upon the tumbler disks 40 and 50 respectively in alignment with the locking pin 19. The handle 48 is then moved through the slot 11 to the point 58 for positioning the notch 47 in alignment with the locking pin 19. 65 When the handle 27 was first placed at the

lower end of the slot 11, the same engaged the lug 33 upon the tumbler disk 30 to position the notch 32 in alignment with the locking pin with the notch 26 in the tumbler disk 24 slightly moved upwardly beyond the locking pin. The handle 27 is finally raised to the point 59 to dispose the edge notch 26 in alignment with the pin and at which time the several notches in the tumbler disks are aligned and receive the locking pin 19 that is shifted by the spring 20. With the locking pin displaced from notch 13 in the shackle leg 7, the shackle leg is permitted to be moved outwardly of the casing a limited distance as illustrated in Figure 6 to effect the release of 70 the shackle. The locking pin 19 is restored to locking position by the lever 54 in a manner previously described.

From the above detailed description of the invention, it is believed that the construction and operation will at once be apparent, and while there is herein shown and described the preferred embodiment of the invention, it is nevertheless to be understood that minor changes may be made therein without departing from the spirit and scope of the invention as claimed.

What I claim as new is:—

1. In a combination padlock of the character described, a lock casing having openings 95 therein for the passage of legs of a shackle, a shackle having its legs extending into the casing openings, a sliding tumbler plate, a locking pin for the shackle leg carried by the plate, a plurality of disk tumblers, each of 100 said tumblers having a peripheral notch with the locking pin selectively engaged in the notches and shackle leg, and a lever spaced from the disk tumblers engageable with the 105 sliding tumbler plate for moving the locking pin into engagement with the shackle leg.

2. In a combination padlock of the character described, a lock casing having openings 110 therein for the passage of the legs of a shackle, a shackle having its legs extending into the casing openings, a sliding tumbler plate, a locking pin for the shackle leg carried by the plate, a plurality of disk tumblers, each of 115 said tumblers having a peripheral notch with the locking pin selectively engaged in the notches and shackle leg, a lever spaced from the disk tumblers engageable with the sliding tumbler plate for moving the locking pin into engagement with the shackle 120 leg, interengaged tumbler lugs on some of said disks, and three operating handles for the tumbler disks carried by the separate disks.

3. In a combination padlock of the character described, a lock casing having openings 125 therein for the passage of legs of a shackle, a shackle having its legs extending into the casing openings, a tensioned sliding tumbler plate normally influenced in a direction of movement away from the shackle leg, a lock- 130

ing pin for the shackle leg carried by the plate, a plurality of notched tumbler disks, operating handles for the disks to position the disks notches in alinement with the locking pin to receive the same, and a lever engageable with the sliding tumbler plate to move the same against spring tension thereon to move the locking pin into engagement with the shackle leg.

10 4. In a combination padlock of the character described, a lock casing having openings therein for the passage of legs of a shackle, a shackle having its legs extending into the casing openings, a tensioned sliding tumbler plate normally influenced in a direction of movement away from the shackle leg, a locking pin for the shackle leg carried by the plate, a plurality of notched tumbler disks, operating handles for the disks to rotate the 15 same, the inner end of the sliding tumbler plate spaced from the shackle bolt being curved, and a lever having a cam end engageable with the curved end of the tumbler 20

plate for moving the locking pin into engagement with the shackle leg.

5. In a combination padlock of the character described, a lock casing having openings therein for the passage of legs of a shackle, a shackle having its legs extending into the casing openings, a tensioned sliding tumbler plate normally influenced in a direction of movement away from the shackle leg, a locking pin for the shackle leg carried by the plate, a plurality of notched tumbler disks, operating handles for the disks to receive the same, the inner end of the sliding tumbler plate spaced from the shackle leg being curved, a lever having a cam end engageable with the curved end of the tumbler plate for moving the locking pin into engagement with the shackle leg, and said casing having slotted openings therein through which the tumbler handles extend.
